Primary Examiner — Kevin Rudzinski(74) *Attorney, Agent, or Firm* — Renner, Otto, Boiselle & Sklar, LLP**(57) CLAIM**

The ornamental design for a light conductive light emitter for a light emitting diode light source, as shown and described.

DESCRIPTION

FIG. 1 is a perspective view of a light conductive light emitter for a light emitting diode light source showing our new design.

FIG. 2 is a front view thereof, the back being a mirror image.

FIG. 3 is a side view of one side thereof, the opposite side being a mirror image.

FIG. 4 is a bottom view thereof; and,

FIG. 5 is a top view thereof.

The top is plain and devoid of surface ornamentation and therefore is not illustrated.

The broken lines in FIGS. 1-3 and 5 are directed to environment structure of unclaimed portions of the light conductive light emitter and form no part of the claimed design.
